UNITED STATES PATENT OFFICE.

EDWIN H. SMYTHE, OF CHICAGO, ILLINOIS, ASSIGNOR TO WESTERN ELECTRIC COMPANY,
OF CHICAGO, ILLINOIS, A CORPORATION OF ILLINOIS.

AUTOMATIC MOTOR-STARTER.

No. 888,759.

Specification of Letters Patent.

Patented May 26, 1908.

Application filed August 17, 1905. Serial No. 274,616.

To all whom it may concern:

Be it known that I, EDWIN H. SMYTHE, citizen of the United States, residing at Chicago, in the county of Cook and State of Illinois, have invented a certain new and useful Improvement in Automatic Motor-Starters, of which the following is a full, clear, concise, and exact description.

My invention relates to a device for gradually and safely regulating the flow of current through a motor when it is being started in motion, and comprises an electromagnet automatically operated according to the varying potentials of the motor armature to successively cut out portions of a resistance included in the armature circuit.

As is well known, if in starting a motor the full strength of the current is suddenly allowed to flow through the motor armature, the parts are likely to be injured, especially if the motor be under a heavy load. Hence various means have been devised for first admitting a weak current to the motor and gradually increasing the current flowing therethrough until the full current strength for which the motor is adapted is reached. It has been customary to include resistances in the armature circuit of the motor through which the current first flows when the switch is closed and to gradually cut out the resistances after the motor has started. One means hitherto devised for cutting out these resistances comprises a brush sliding over a series of contacts connected to the resistance so that increased portions of said resistance are short-circuited as the brush moves over the contacts. Another well known means comprises a series of electromagnets which are arranged to be successively operated as the counter electromotive force of the motor increases, and so connected as to control the resistance in the motor circuit. While this latter means overcomes the sparking and other objectionable features of the first described means, and furthermore regulates the admission of current in proportion to the load, it is itself open to objections. A number of electromagnets are required, one for each resistance to be cut out. Moreover, as the resistances are cut out by a short circuit through the contacts of the armatures with their electromagnets, the positiveness of the contact depends on the strength of the current flowing through the electromagnet. This in turn varies as the speed of the motor

increases. Hence when the circuit cutting out a resistance is closed a strong contact does not at first result.

In my invention a series of bridging members are adapted to successively cut out resistances in the motor armature. The operation of these members is controlled by a series of cams adapted to regulate the movement of the contact brushes thereof into bridging position one after the other as the armature of the motor speeds up. A solenoid, energized when the switch connecting the motor to the mains is closed in the act of starting up the motor, operates to place the entire series of bridging members in condition to have their closure regulated by the cams, the movements of which are controlled by a second solenoid, arranged to operate on the difference of potential caused by the speeding up of the motor, the core of the solenoid being gradually moved to rotate the cams and thus control the operation of the brushes in cutting out the resistance in the armature circuit. The positiveness of the contact of the brush is dependent upon a spring or other mechanical means, and hence a good contact results. It will be seen, therefore, that after the bridging members are brought by the action of a solenoid, or other suitable means, into operative condition, a single electromagnet serves to regulate the operation of said bridging members to gradually cut out the resistance in the motor armature, and that a positive, direct and uniform contact is produced when a resistance is cut out. Moreover, by my invention, the rapidity with which the full current strength is turned on the motor is automatically dependent upon the load.

I will describe my invention more particularly by reference to the accompanying drawings, in which

Figure 1 is a diagram showing the course of the main and shunt currents through the motor and the starting device; Fig. 2 is a front elevation of the starting device; Fig. 3 is a side elevation thereof; Fig. 4 is a sectional view on the line 4—4 of Fig. 2, showing the position of the parts prior to the closing of the switch which connects the motor to the mains; and Fig. 5 is a corresponding view, showing the position of the parts after the motor switch is closed and after the device has operated to cut out part of the resistance.

The same letters of reference are used to designate the same parts wherever they are shown.

As illustrated in Fig. 1, when the switch is closed to connect the motor with the mains, the current from the terminals will be closed through the conductor 1, the shunt field magnet coils A, and conductor 2. The main circuit is also closed through the conductor 10 1, motor armature M, resistance R and conductor 2. A shunt circuit leads from conductor 1 through conductor 1^a, which includes the windings of the solenoid S to conductor 2. A shunt circuit also leads from 15 conductor 1 through the conductor 1^b, which includes the high resistance windings of the solenoid S'.

It is apparent that immediately upon the switch being closed to start the motor, a 20 comparatively weak current passes through the motor, owing to the resistance R through which it must flow. At the same time current flowing through the solenoid S causes it to draw in its core or plunger a. Said core 25 at its upper end has a slotted pivoted connection with one end of an arm e, the other end of which is keyed to a shaft b, having suitable bearings in a stationary bracket secured to the framework. Hence when the 30 magnet S is excited and moves its core a, the shaft b is partially rotated.

Upon the shaft b are loosely mounted a series of bifurcated levers i, each carrying at 35 its lower end a roller i' adapted to engage an arm g. The arms g and k are pivotally connected by the rod l, supported by brackets secured to the framework. A link m connects arm k and lever i, the parts i, g, k and m constituting a toggle lever. When the 40 switch to the motor is open, the parts are in the position shown in Figs. 1 and 4, the arm g being held against the roller i' by the spring i², and the toggles not being in operative relation with the cams d. In this position the 45 pin o is in contact with the key p on the lever i, and holds the roller i' in the recess g' in the arm g. However, upon the closing of the motor switch, the core a of the solenoid S is drawn inward against the force of the 50 coiled spring s. This produces a partial rotation of the shaft b, in the manner hereinbefore described, the pin o is moved from engagement with the stop p, and a spring n, secured to the shaft and bearing against the 55 link m comes under tension and causes the roller i' to tend to ride upward on the arm g, pressing said arm downward into operative relation with the cam d. The spring i², however, partially counterbalances the 60 downward pressure on the arm g and prevents too great a frictional engagement of said arm with the cam. As shown in the drawing, there is a series of these springs n, one associated with each toggle lever.

65 The cams d are keyed to a shaft e, having

its bearings in brackets secured to the framework. Keyed to the shaft e is the arm e', and to the other end of said arm is pivotally secured the core a' of the solenoid S'. When the solenoid S' attracts its plunger or core piece, the shaft e and the cams d keyed thereto are rotated. The cams are so positioned on the shaft that the depressed faces f thereof are successively presented to the arms g as the cams are rotated, and thereby the bridging members h are successively operated, in a manner hereinafter more fully described, to close the circuit and cut out part of the resistance R of the armature circuit. 70 75

The magnet S' is so wound that the counter electromotive force developed by the armature of the motor when the armature circuit is closed will operate to energize the solenoid S' sufficiently to partially draw in the core a' against the pressure of the spring s'. This causes a partial rotation of the shaft e and its cams d, to bring the depression f of the cam beneath the arm g, so that the arm sinking into the depression permits the tension of the spring n to cause the roller i' to ride upon the arm and to operate the arm k through the link m. The contact points h of the bridge member are thus firmly seated, so as to short-circuit a portion of the resistance R. 80 85 90

The increased flow of current through the 95 motor resulting from the cutting out of a portion of the resistance, increases the counter electromotive force and thereby more strongly energizes the electromagnet S', which draws its core piece a' still farther inward, and thereby further rotates shaft e and brings the depression of the second cam in position beneath the second arm g, whereupon the second bridge member is caused to 100 cut out another portion of the resistance R. 105 As the amount of current flowing through the motor increases as resistance is cut out of the motor armature, the counter electromotive force likewise increases, and the resistance R will be gradually cut out, in the manner above 110 described, at which time the motor will have attained its proper speed and be capable of receiving the full amount of the current supplied by the mains.

It will be observed that the rapidity with 115 which the resistance in the motor armature is cut out by my motor starting device is thus automatically determined, and is inversely proportional to the load. With a light load, the current is rapidly turned on; with a 120 heavy load, the current is more slowly admitted. Thus, injury to the motor from too sudden admission of the current therethrough is prevented.

When the switch is operated to disconnect 125 the motor from the mains, my starting device is restored to the position shown in Figs. 1 and 4, in the following manner: The solenoid S being no longer energized, the spring s forces out the core a, thus rotating the shaft 130

5 *b* in a direction reverse to that before described. The pin *o* on the shaft contacts with a stop *p* of the lever *i* and forces the lever downward until the roller *i'* rests in the groove *g'* in the arm *g*, in which position the downward pressure of the roller *i'* upon the arm *g*, due to the pin *o* on shaft *b* pressing against stop *p* on the lever *i*, is counterbalanced by the upward pull of the spring *i²*, 10 and the parts are out of operative contact with the cams *d*. The core *a'* being likewise forced out by the spring *s'* of the solenoid *S'*, rocks the shaft *e* and restores the cams *d* to their initial position.

15 I claim—

1. The combination with an electric motor and its circuit, of a resistance in said circuit, a series of switch members each adapted to cut out a portion of the resistance, a magnet 20 adapted to be controlled by varying currents, and cam mechanism actuated by said magnet to regulate the successive operation of said switch members.

2. The combination with an electric motor 25 and its circuit, of a resistance in the motor circuit, a series of switch members each adapted to cut out a portion of the resistance, means tending to close said switch members, means normally obstructing the closure 30 thereof and an electromagnet energized according to the varying potential of the motor armature, for removing in succession said switch obstructing means.

3. In a motor starting device, the combination with the motor, of a resistance included in the circuit thereof, a series of switches each adapted to cut out a portion of said resistance, electromagnetic means operated upon the closure of the motor circuit for automatically placing said switches 40 under tension tending to close the same, means normally obstructing the closure of said switches, and an electromagnet energized according to the varying potential of 45 the motor armature for removing in succession said switch obstructing means.

4. In a motor starting device, the combination with the motor, of a resistance included in the circuit thereof, a solenoid automatically energized according to the varying potential of the motor armature, a movable core for said solenoid, a shaft having a series of cams mounted thereon, a connection between said core and shaft whereby the movement of the core rotates the cams, and a series of toggles automatically operated upon the rotation of said cams to successively short circuit portions of said resistance.

5. The combination with an electric motor 50 and its circuit, of a resistance in the motor circuit, a series of toggle switch members each adapted to cut out a portion of the resistance, an electromagnet, means operated by said magnet for putting the switch members under tension tending to close the same,

an electromagnet energized according to the varying potential of the motor armature, and cam mechanism controlled by the energization of said second named magnet for regulating the successive closing of said switch members. 70

6. The combination with an electric motor and its circuit, of a resistance in the motor circuit, a series of switch members each adapted to cut out a portion of the resistance, 75 a solenoid adapted to be controlled by varying currents, a movable core for said solenoid, and cam mechanism controlled by the movement of said core, said cam mechanism being arranged to control the successive operation of said switch members. 80

7. In a motor starting device, the combination with the motor, of a resistance included in the circuit of the motor, a solenoid with a movable core automatically controlled 85 by varying currents, a shaft having a series of cams secured thereto, a connection between the core and the shaft whereby the movement of the core rotates the cams, and a series of toggles automatically operated 90 upon the rotation of said series of cams to successively cut out portions of said resistance.

8. The combination with an electric motor and its circuit, of a resistance in the motor circuit, a series of toggle switch members 95 each adapted to cut out a portion of the resistance, a solenoid having a movable core for putting the switch members under tension tending to close the same, a second solenoid having a core the movement of which is automatically regulated according to varying currents, and means actuated by the movement of said second named core for controlling the successive operation of said series of switch members. 100

9. In a motor starting device, the combination with the motor, of a resistance included in the circuit thereof, a series of switch members each adapted to cut out a portion of said resistance, means for initially putting said members under tension tending to close the same, a series of cams arranged to successively control the operation of said members, a solenoid having a core the movement of which is automatically regulated 110 according to varying currents, and a connection between said core and cams; whereby the movement of the core rotates the cams and thereby permits the successive automatic operation of the switch members to 120 cut out the resistance.

10. The combination with an electric motor and its circuit, of a resistance in the motor circuit, a series of switch members each adapted to cut out a portion of the resistance, 125 a shaft upon which said members are mounted, a solenoid having a core the movement of which is adapted to rock said shaft and put said switch members under tension tending to close the same, a series of cams 130

normally preventing the closure of said switch members, a shaft upon which said cams are mounted, and a solenoid having a core the movement of which is automatically regulated according to varying currents, and which is adapted to rotate said shaft to rotate said cams; whereby the switch members are successively actuated to cut out said resistance as the speed of the motor armature increases.

11: In a motor starting device, the combination with the motor, of a resistance included in the circuit thereof, a shunt circuit including a solenoid, a plunger moved by the solenoid, a rock-shaft carrying a series of toggle levers having contact bridging members thereon, a connection between the shaft and the plunger whereby the movement of the latter rocks the shaft and puts said toggles under tension, a second solenoid adapted to be energized according to varying currents, a plunger moved by said second solenoid in proportion to the energization thereof, a shaft carrying a series of cams thereon corresponding to said series of toggles and normally preventing the operation of the same, said cams being arranged to control the successive operation of the toggles, and a connection between said second named shaft and plunger, whereby the movement of the plunger rotates the cams and automatically regulates the successive cutting out of portions of said resistance.

12: In a motor starting device, the combi-

nation with the motor, of a resistance included in the circuit thereof, a shunt circuit including a solenoid, a rock-shaft having a series of pins and springs thereon, a series of toggle levers loosely mounted on said shaft, bridging members carried by said toggle levers, a connection between the shaft and the plunger, whereby the outward movement of the plunger causes an engagement of said pins with said levers and places the latter in an inoperative position, and whereby the movement of the plunger in the reverse direction releases the pins and places the springs under tension which tends to operate said bridging members, a series of cams normally preventing the actuation of said bridging members, said cams being arranged to control the successive actuation of the bridging members, a shaft upon which said cams are mounted, a second solenoid having a core the movement of which is automatically regulated according to varying currents and which is adapted to rock said shaft to rotate said cams; whereby the switch members are successively and automatically actuated to cut out said resistance as the speed of the motor armature increases.

In witness whereof, I hereunto subscribe my name this 31st day of July, A. D., 1905.

EDWIN H. SMYTHE.
